UNITED STATES PATENT OFFICE.

SIDNEY P. LYON, OF DAYTON, OHIO.

TOOL FOR PLACING RIVETS.

Application filed January 11, 1922. Serial No. 528,517.

To all whom it may concern:

Be it known that I, SIDNEY P. LYON, a citizen of the United States, residing at Dayton, in the county of Montgomery and State of Ohio, have invented certain new and useful Improvements in Tools for Placing Rivets, of which the following is a specification.

This invention relates to a tool for placing rivets inside of tubes and furnishing a backing for the same.

It is very difficult to place a rivet through a tube from a point within the tube. The problems thus presented and like problems of positioning rivets in places equally inaccessible are frequently confronted in practice. My invention aims to provide a tool or mechanism of simple construction and operation whereby rivets or the like may be readily positioned in the holes provided for them and backed for the external riveting operation.

The invention is described in the following specification, in connection with the accompanying drawings, in which:

Fig. 1 is a central longitudinal section of an embodiment of the invention in operative position within a tube; and

Figure 2 is a transverse sectional view on the line 2—2 of Fig. 1.

The numeral 10 designates a tube having a hole 11 through which it is desired to insert a rivet 12 so that the head of the rivet will bear against the inside of the tube. For this purpose my invention provides a tool the normal dimensions of which are slightly smaller than the inside diameter of the tube so that the tool may be slidingly positioned within the tube.

From the following description it will be seen that my device is comprised as follows: A bearing block 13 having an arcuate passage 14 formed therethrough is provided. This arcuate passage passes through the cylindrical bore of an extension 15 of the block 13, which extension projects from one end of the block and has a recess formed therein adapted to receive one end of a magazine tube 16, which is fitted therein

in such a manner that the interior of the magazine tube is in fact, a continuation of the passage 14. The other end of the magazine tube is closed by a detachable cap 17. A coil spring 18 within the magazine tube bears at one end against the cap and at the other end against the last rivet of a row

of rivets contained within the passage 14 and tube 16. The spring 18 tends to feed the outermost rivet outwardly into any opening which may come into registration therewith, the force of the spring being transmitted by successive rivets in the magazine. The upper surface of the block 13 is provided with a groove 19 which terminates at one end at an abutment 20 having a curved inner surface corresponding to the curvature of a rivet head. A recess 21 is formed through the lower part of the block 13 and the upper portion of the block is extended rearwardly and terminates in a boss 22 of cylindrical bore which boss marks the rear end of said recess. The forward end of the recess is defined by the vertical and horizontal surfaces 23, 24 respectively. An opening passes longitudinally through the boss 22 and a shaft 25 is rotatably mounted in said opening. A single spiral groove 26 of steep pitch is cut in the shaft and a lug or spiral thread 27 on the cylindrical boss engaging said groove is adapted to advance the shaft quickly when a rotative movement is imparted thereto.

A lock block 28 having a slightly concave lower surface ending in spaced supporting legs 28' and a wedge-shaped inner surface 29, is adapted to cooperate with a spreading element in the form of a block 30 having a wedge shaped surface 31 and an upper flat surface 32. A stub shaft 33 projecting from the rear face of spreading element 30 is received within a socket formed in the forward end of shaft 25. The stub shaft is provided with an annular groove 34 in which a set screw or pin 35 passing through the shaft 25 engages, so as to permit rotational movements of shaft 25 independently of the stub shaft and move the spreading element longitudinally with the shaft 25. A leaf spring 36 having one end thereof connected to lock block 28 and the other end to the boss 22 tends to return the lock block to normal position after each expanding operation. The bearing block 13, spreader block 30 and lock block 28 comprise an expandible head.

The cylindrical boss 22 has a rearwardly extending annular flange 37 which surrounds the shaft 25 in spaced relation thereto. The shaft 25 terminates slightly rearwardly of the flange in a reduced cylindrical portion 38 carrying a transverse pin 39. The latter engages in a transverse slot 40

formed in the inner end of an operating shaft 41. This shaft is located within a tubular casing 42 one end of which is pressed within the annular flange 37. A knurled 5 hand grip 43 slips over the outer end of the tubular casing and is attached thereto. This hand grip includes a plate 44 which closes the casing except for a central aperture through which the shaft 41 extends. 10 The hub 45 of an actuating handle 46 is attached on the projecting end of the shaft 41 by a pin 47.

In operation, the apparatus or tool will be shifted within the tube 10 until the rivet 15 finds the desired hole, when the spring of the magazine will force the rivet into the hole. By shifting the whole apparatus further into the tube the abutment 20 is reached, the curved side of which engages a portion 20 of the rivet head, and the bearing block 13 engaging the rivet head in groove 19 is ready to act as an anvil for the external riveting operation. The grip 43 is now held stationary by one hand of the operator and the 25 handle 46 is turned with the other hand. The pin 39 imparts the rotary movement of shaft 41 to shaft 25 and as a result, the latter is advanced longitudinally owing to the engagement of spiral groove 26 and lug 27. 30 This longitudinal movement of shaft 25 is communicated to the spreading element which is forced between the block 13 and lock block 28. The wedge shaped surfaces 25 29 and 31 coact to push the bearing block 13 outwardly and force the rivet head tightly against the inner side of the tube. The expanding head composed of the blocks 13, 28 and element 30 thus acts to furnish a firm backing for the rivet during the riveting 40 operation. Upon the completion of the riveting operation the grip 43 is grasped by one hand and the handle 46 is turned in the opposite direction by the other hand. This action withdraws the wedge-shaped spreading 45 element and permits the expandable head to contract to normal position.

It will be understood that the particular construction described and shown has been chosen for illustrative purposes merely and 50 that the invention as defined by the claims hereunto appended may be otherwise embodied and applied without departing from the spirit and scope thereof.

I claim:

55 1. In a tool of the class described, the combination of an expandable head having a bearing block provided with a passage therethrough, terminating in a groove provided with a concaved recess at one end a tubular 60 container communicating with said passage, a spring in said container, rivets in said passage and container subject to the pressure of said spring, and means for expanding said head.

65 2. In a tool of the class described, the

combination of an expandable head having a bearing block provided with a passage terminating in an arcuate groove having a concaved recess at one end thereof, means for feeding rivets when the block is properly located so that the rivet heads are positioned in said recess, and means for expanding said head. 70

3. In a tool of the class described, the combination of an expandable head including a longitudinally movable spreading element, rotatable operating mechanism, and means associated therewith for converting the rotational movements of said mechanism into movements of said spreading element longitudinally with respect to said block. 75

4. In a tool of the class described, the combination of an expandable head including a longitudinally movable spreading element, a rotatable and longitudinally movable shaft, a connection between said shaft and element adapted to transmit only the longitudinal movements of the shaft to said element, an operating shaft, a connection between said shafts adapted to transmit rotary motion and permit relative longitudinal movements thereof, and means for moving said first named shaft longitudinally upon rotation of said operating shaft. 80

5. In a tool of the class described, the combination of an expandable head, a rotatable operating shaft, a spreading element revolvably mounted on said operating shaft, means operatively connecting said block to said shaft in such a manner that rotation of 95 said shaft results in relative longitudinal motion between said shaft and said block, and means for holding said head from rotation during the actuation of said shaft. 100

6. In a tool of the class described, the combination of an expandable head, a rotatable operating shaft, a spreading element revolvably mounted on said operating shaft, means operatively connecting said block to said shaft in such a manner that rotation of 105 said shaft results in relative longitudinal motion between said shaft and said block, and means for holding said head from rotation during the actuation of said shaft, said block being provided with a lug adapted to 110 travel in a spirally cut groove in said shaft in such a manner that the rotary motion of said shaft results in relative longitudinal motion between said block and said shaft. 115

7. In a tool of the class described, the combination of an expandable head, a rotatable operating shaft, a spreading element revolvably mounted on said operating shaft, means operatively connecting said block to said shaft in such a manner that rotation of said 120 shaft results in relative longitudinal motion between said shaft and said block, and means for holding said head from rotation during the actuation of said shaft, said block being 125 provided with a lug adapted to travel in a 130

spirally cut groove, in said shaft in such a manner that the rotary motion of said shaft results in relative longitudinal motion between said block and said shaft, said spreading element being revolvably mounted on but fixed against relative longitudinal motion with respect to said shaft.

8. In a tool of the class described, the combination of an expansible head, a rotatable operating shaft, a spreading element revolvably mounted on said operating shaft, means operatively connecting said block to said shaft in such a manner that rotation of said shaft results in relative longitudinal

motion between said shaft and said block,¹⁵ and means for holding said head from rotation during the actuation of said shaft, said block being provided with a lug adapted to travel in a spirally cut groove in said shaft in such a manner that the rotary motion of ²⁰ said shaft results in relative longitudinal motion between said block and said shaft, and arcuate passageway in said block terminating in a substantially hemispherical recess for the purpose described.²⁵

In testimony whereof I affix my signature.

SIDNEY P. LYON.
